United States Patent Office

Des. 188,440
Patented July 19, 1960

188,440

DIAPER PAIL LID

Mark S. James, Jr., Pittsburgh, Pa., assignor to Mark Laboratories, Inc., Pittsburgh, Pa.

Filed Jan. 21, 1958, Ser. No. 49,342

Term of patent 14 years

(Cl. D58—17)

Fig. 1

Fig. 5 is an enlarged detail view in horizontal section taken on line 5—5 of Fig. 2.

I claim:

The ornamental design for a diaper pail lid, substantially as shown.
